(57) **CLAIM**

The ornamental design for a lift for a drum in an electronic washing machine, as shown and described.

DESCRIPTION

FIG. 1 is a front, left perspective view of the lift for a drum in an electronic washing machine showing our new design;

FIG. 2 is a front view thereof;

FIG. 3 is a rear view thereof;

FIG. 4 is a left side view thereof, the right side view being a mirror image thereof;

FIG. 5 is a top plan view thereof; and,

FIG. 6 is a bottom view thereof.
